(57) **CLAIM**

The ornamental design for a hair adornment, as shown and described.

DESCRIPTION

FIG. 1 is an enlarged front elevational view of a hair adornment showing my new design, the braid is drawn broken away for ease of illustration;
FIG. 2 is a right side elevational view thereof;
FIG. 3 is a left side elevational view thereof;
FIG. 4 is a back elevational view thereof;
FIG. 5 is a top plan view thereof;
FIG. 6 is a bottom plan view thereof;
FIG. 7 is an enlarged front elevational of a second embodiment of a hair adornment showing my new design, the braid is drawn broken away for ease of illustration;
FIG. 8 is a right end elevational view thereof, the left end elevational view thereof being a mirror image;
FIG. 9 is a back elevational view thereof;
FIG. 10 is a top plan view thereof;
FIG. 11 is a bottom plan view thereof;
FIG. 12 is an enlarged front elevational view of a third embodiment of a hair adornment showing my new design, the braid is drawn broken away for ease of illustration, the right and left views of the hair clip being the same as FIG. 8;
FIG. 13 is a back elevational view thereof;
FIG. 14 is a top plan view thereof;
FIG. 15 is a bottom plan view thereof;
FIG. 16 is an enlarged front elevational view of a fourth embodiment of a hair adornment showing my new design, the braid is drawn broken away for ease of illustration, the right and left views of the hair clip being the same as FIG. 8;
FIG. 17 is a rear elevational view thereof;
FIG. 18 is a top plan view thereof;
FIG. 19 is a bottom plan view thereof;
FIG. 20 is a front elevation view of a first embodiment of the hair adornment;
FIG. 21 is a front elevation view of a second embodiment of the hair adornment;
FIG. 22 is a front elevation view of a third embodiment of the hair adornment; and,
FIG. 23 is a front elevation view of a fourth embodiment of the hair adornment.
